HYDRAULIC PUMP OR MOTOR

Elek K. Benedek, Bucyrus, Ohio

Application March 26, 1936, Serial No. 71,005

1 Claim. (Cl. 103—161)

This invention relates to hydraulic pumps or motors and more particularly to hydraulic pumps or motors of the kind comprising a plurality of radial piston and cylinder assemblies mounted for rotation about a pintle or the like. Pumps or motors of this general class or description are well known in the art and may be of either the fixed or variable discharge type. As will be understood from the description which follows, improvements in accordance with my present invention may be embodied in pumps or motors of this general class, whether they be of the fixed or variable discharge type.

Due to the high pressure working conditions usually prevalent, there is considerable heating of the pressure fluid, and consequently appreciable heating and expansion of the pump or motor parts. A fundamental requirement for efficient operation is the maintaining of accurately predetermined clearances, particularly between the cylinder barrel and the pintle about which it rotates. In most such pumps, the cylinder barrel and pintle are formed with ports which cooperate to effect the necessary valving of the flow to and from the cylinders. Hence, if the clearance between the cylinder barrel and the pintle is allowed to become too large, due to expansion of one or both of the elements, or to any other cause, there will be a pressure loss directly diminishing the capacity of the machine and producing other undesirable results such as noisy and vibratory operation. On the other hand, if the clearance is made too small, it will not be possible to maintain the oil film necessary for quiet running and efficient operation. The maintaining of just the correct amount of clearance therefore is very important.

An object of the present invention is to provide an improved pump or motor structure including bearings supporting the cylinder barrel with respect to the pintle and the casing in a novel manner resulting in smoother and more efficient operation and longer life than other pumps or motors of the class referred to.

Another object is to provide an improved pump or motor structure in which the clearance between the cylinder barrel and the pintle may be maintained substantially constant, irrespective of unequal expansion or contraction of different parts. Other objects will become apparent from a reading of the following description, the appended claim, and the accompanying drawings, in which:

Figure 1 is an axial section of a pump or motor embodying the invention. Figure 2 is a similar view showing the invention embodied in a somewhat different form. Figure 3 is a similar view showing the invention embodied in still a different form. Figure 4 is a transverse section taken on the line 4—4 of Figure 1. Figure 5 is a diagrammatic view illustrating schematically

one principle of embodiment of the invention, and Figure 6 is a diagrammatic view illustrating schematically a slightly different principle of embodiment.

One structure embodying the invention in practical form is shown in Figures 1 and 4 as including a casing A, a fixed cantilever pintle B, a cylinder barrel C mounted for rotation about the pintle, a plurality of radially disposed pistons D, and means generally designated E for effecting reciprocation of the pistons within the associated cylinder bores in the barrel C. The structure will be described as a pump but it will be understood that it may function as a motor also.

The mounting and supporting of the cylinder barrel for rotation about the fixed pintle in accordance with the invention claimed in this application will be described later. Attention first will be directed to the general structural organization of parts not claimed in this application, but an understanding of which will be required in order to render fully apparent the features herein described as constituting the invention claimed in this application. The casing A comprises separable sections 1 and 2 secured together by means of bolts 3. The reaction means E comprises rings 4—4 secured together by means of bolts 5 and maintained in properly spaced relation by spacers 6. Heads 6^a on the pistons are connected in driving relation to the rings 4—4 by pins 7 mounted in the heads by anti-friction bearings 8 and having reduced end portions projecting into opposed track grooves formed in the rings 4—4. Anti-friction bearings 9 mount the ring assembly 4—4 within an outer reaction ring 10 which is supported for shifting movements by means of rods 11 passing through apertures in the casing and by pads 12 on the ring 10 which are mounted for sliding movement on pads 13 on the casing. As is well understood in the art, when the cylinder barrel is rotated with the reaction means E in an eccentric position relative to the pintle, the pistons D will be caused to reciprocate within their respectively associated cylinders 14. The cylinders communicate by means of ports 15 with cooperating valve ports 16 in the pintle for valving the flow of fluid to and from the cylinders in a manner well known in the art.

In accordance with the invention claimed in this application, the cylinder barrel C shown in Figures 1 and 4 is supported in a novel manner permitting axial expansion relatively between the casing and the pintle or the cylinder barrel without disturbing the desired close clearances and at the same time there being no appreciable play or looseness in the bearing parts supporting the cylinder barrel with respect to radial loads or stresses. In the form shown by way of illustration in Figures 1 and 4, the pintle B includes a

cylindrical anchoring portion 17 which has a press fit or is otherwise securely fixed within a bore 18 in the casing section 1, the pindle being formed with a flange 19 abutting against the casing section 1 at the inner end of the bore 18 for locating the pindle properly. Beyond the flange 19 the pindle includes a cylindrical bearing portion 20, a tapered portion 21, and an outer cylindrical bearing portion 22.

10 It will be understood that it is desirable to maintain a very close running fit between the tapered portion 21 of the pindle and the associated cooperating tapered bore of the cylinder barrel. This is desirable in order to provide for the formation of an oil film between the tapered portion 21 and the cylinder barrel, thus providing for effective sealing of the fluid. Obviously, if the clearance is too large, fluid will leak along the pindle resulting in a pressure loss. On the other hand, if the clearance is too small there is danger that the parts will have rubbing metal-to-metal contact resulting in scoring and damaging of either the pindle or the cylinder barrel or both. Therefore, in accordance with my invention I so connect the cylinder barrel and pindle as to maintain a substantially fixed desirable clearance and yet to permit axial expansion of these parts such as would be due to heating of the fluid. To this end I provide bearings between the pindle and the cylinder barrel at both ends of the latter, the bearings at at least one end being so arranged as to constrain that end of the pindle to move axially together with the associated end of the cylinder barrel. As shown, the inner end of the cylinder barrel, i. e., that nearest the fixed end of the pindle, is supported for rotation about the latter by an anti-friction bearing 23 which comprises an inner race 24 surrounding the bearing portion 20 of the pindle and an outer race 25 fitting within a counter-bore 26 in the cylinder barrel. At the outer or free end of the pindle there is provided an anti-friction bearing 27 comprising an inner race 28 surrounding the bearing portion 22 of the pindle and clamped between a shoulder 29 and a washer 30 drawn up by a nut 31; and an outer race 32 located within a counter-bore 33 in the cylinder barrel. A drive shaft 34 is connected to the cylinder barrel by means of a coupling flange 35 secured to the cylinder barrel by bolts 36 the shaft thereby in effect constituting a part of the cylinder barrel. An annular rib 37 on this coupling flange engages the outer bearing race 32 and locks the latter in the counter-bore 33. It will be observed that there can be no relative axial movement between the cylinder barrel and the outer or free end of the pindle. However, I have provided for simultaneous or conjoint axial movement of the barrel and pindle in order to permit expansion of the parts by causes such as heating. The expansion is provided for by mounting the drive shaft within the casing by a bearing arrangement which, in the form shown, comprises an inner race 38 clamped against a shoulder 39 by means of a nut 40, the race being grooved peripherally for the reception of rollers 41 which are surrounded by and in engagement with an outer race 42 clamped against a casing shoulder 43 by a rib 44 on a cap member 45.

50 The bearing face 46 of the outer race 42 is formed to permit relative sliding movement of the rollers 41 in a direction parallel to the axis of the pindle. Preferably the race is sloped off or cambered at its edges, this arrangement preventing the formation of a worn groove.

It is apparent that expansion of the pindle and cylinder barrel or casing in an axial direction due to heating or other causes can take place readily without disturbing any of the essential clearances and without requiring any looseness of the bearings transmitting radial stresses. This results in elimination of vibration and pressure loss due to fluid slip or leakage, and in more quiet and efficient operation of the pump as a whole.

Figure 2 shows a pump or motor embodying the invention in principle similar to the pump or motor shown in Figure 1, but differing as to certain specific details. In the Figure 2 form, all the parts are similar to corresponding parts in the Figure 1 form with the exception of the bearings interposed between the pindle and the cylinder barrel, which bearings differ in some specific respects. Therefore, in Figure 2, the parts which are the same as corresponding parts in Figure 1 are designated by reference characters which are the same as those applied to corresponding parts in Figure 1 with the exception that such reference characters in Figure 2 are primed. Thus, the casing sections 1' and 2' of Figure 2 correspond to the casing sections 1 and 2 of Figure 1. Similarly, the reaction rings 4'-4' of Figure 2 correspond to the reaction rings 4-4 of Figure 1.

The difference of the Figure 2 form over that shown in Figure 1 resides in the provision of tapered roller bearings in place of the ball bearings for supporting the cylinder barrel on the pindle. In the Figure 2 form an inner race 47 is mounted on the cylindrical bearing portion 20' of the pindle 17' and is provided with an inclined groove 48 which receives roller bearings 49. An outer race 50 is formed with an inclined bearing face 51 cooperating with the rollers 49 and is mounted within the counter-bore 25' in the cylinder barrel. At the outer end of the pindle an inner race 52 is clamped between the shoulder 29' and the washer 30' and is provided with an inclined groove 53 which receives roller bearings 54. An outer race 55 formed with an inclined face 56 is positioned within the counter-bore 33' in the cylinder barrel. The bearing for mounting the drive shaft 34' and, consequently, the cylinder barrel within the casing comprises parts 38', 39', 40', etc. which correspond to and are the same as parts 38, 39 and 40 described with reference to Figure 1. It will be observed that as broadly considered the same functional results and advantages are obtained by the use of the construction shown in Figure 2 as are set forth above with reference to the construction shown in Figure 1. In either construction it is preferable that there be no slackness in a radial direction between any of the bearing or roller elements and the associated races. The novel constructions embodying the claimed invention make it possible and desirable to provide initially and to maintain snugly fitting bearings for transmitting radial stresses.

Figure 5 shows schematically the principle underlying the invention as embodied in the forms shown in Figures 1 and 2. Thus, the casing or fixed pump part is designated *k*, the pindle *l*, the cylinder barrel *m*, the bearings between the cylinder barrel and the pindle *n*, and the bearing between the cylinder barrel and the casing, *o*. From a consideration of Figure 5, it is apparent that the invention may be embodied in pumps having straight or non-tapered pintles as well as in those in which the pindle is tapered. However, the functional advantages resulting

from bearing arrangements in accordance with my invention are more outstanding in pumps including tapered pintles.

Figure 3 shows an embodiment of the invention in which the cylinder barrel is so mounted within the casing as to be constrained against bodily axial movement with respect to the casing but is supported on the pintle in such manner as to permit a small amount of relative movement axially with respect to the pintle. The arrangement is such as to permit this small movement between the pintle and cylinder barrel without its being necessary to provide any appreciable radial looseness or play in the bearings. The pump shown in Figure 3 includes a casing A'', a pintle B'', cylinder barrel C'', a plurality of radially disposed cylinders D'', and reaction means generally designated E'' for effecting reciprocation of the pistons. The pump casing includes sections 1'' and 2'' secured together by means of bolts 3''. The reaction means E'' includes inner reaction rings 4'' secured together by means of bolts 5'' and maintained in spaced relation by means of spacers 6''. Pins 7'' mounted in the piston heads by means of anti-friction bearings 8'' are provided with reduced end portions which project into annular track grooves conjointly formed by the rings 4'' and associated inside track ring members IV-IV.

Anti-friction bearings 9'' mount the rings 4'' within an outer reaction ring 10'' supported for shifting movements by means of rods 11'' passing through the casing section 1''. The pistons D'' are mounted for reciprocation in cylinders 14'' in the cylinder barrel C'' and communicate with ports 15'' adapted to coact with pintle ports 16'' for valving the flow of fluid.

The pintle B'' is provided with a cylindrical anchoring part 17'' having a press fit or being otherwise securely mounted within a bore 18'' in the casing half 1''. Beyond the anchoring portion the pintle is formed with a cylindrical bearing portion 20'', a tapered portion 21'', and an outer cylindrical bearing portion 22''.

A roller bearing assembly 23'' is mounted adjacent the inner end of the pintle with its inner race 24'' surrounding the cylindrical bearing portion 20'' of the pintle and being grooved for the rollers. The outer race 25'' likewise is grooved for reception of the rollers and is mounted within a counter-bore 26'' in the cylinder barrel. It will be observed that the races 24'' and 25'' are adapted to have a small amount of sliding movement with respect to the pintle and the cylinder barrel, respectively.

A roller bearing assembly 27'' located adjacent the outer end of the pintle has its inner race 28'' surrounding the cylindrical portion 22'' of the pintle and clamped between a shoulder 29'' on the pintle and a washer 30'' drawn up by a nut 31''. The inner race 28'' is provided with a groove for receiving the rollers as is also the outer race 32'' which is positioned within a counter-bore 33'' in the cylinder barrel. The outer race is so positioned as to be movable to a limited extent axially with respect to the cylinder barrel.

In this embodiment of the invention, the drive shaft and cylinder barrel are so mounted as to be constrained against bodily axial movement with respect to the casing. As shown, the drive shaft 34'' is provided with a coupling flange 35'' secured to the cylinder barrel by means of bolts 36'', and is held centered with respect to the latter by means of an annular rib 37''. The shaft

34'' and, consequently, the cylinder barrel are maintained against radial and axial movements with respect to the casing by means of an anti-friction bearing including a race 38'' clamped against a shoulder 39'' of the shaft by means of a nut 40'' and grooved for the reception of ball elements 41''. An outer race likewise grooved for the reception of the ball elements is clamped against a shoulder 43'' of the casing by means of a rib 44'' on a cap member 45''. Thus, no bodily axial shift or movement of the shaft and cylinder barrel can take place. However, as previously stated, the bearings between the pintle and the cylinder barrel are such as to permit slight relative axial movement therebetween in order to provide for unequal expansion of the parts.

The principle underlying this embodiment of the invention is shown schematically in Figure 6, in which k'' indicates the casing, l'' the pintle, m'' the cylinder barrel, n'' the bearings between the pintle and cylinder barrel at the opposite ends of the pintle, and o'' the bearing between the cylinder barrel and the casing which constrains the cylinder barrel against both axial and radial movements relative to the casing. From a consideration of this figure, it will be apparent that advantages resulting from the present invention may be obtained in pumps or motors including a straight or cylindrical pintle as well as in pumps or motors equipped with tapered pintles.

It will be understood that the embodiments of my invention disclosed herein are generically illustrative of other forms and that various changes in the specific construction and arrangement of the parts may be made without departing from the invention as defined in the claim.

I claim:

In a hydraulic pump or motor, the combination of a casing having first and second side walls and an annular wall integral with said first side wall, a tapered cantilever pintle rigidly secured to said first side wall and extending into said casing, a cylinder barrel mounted for rotation about said pintle, a drive shaft aligned with said pintle, an anti-friction bearing assembly interposed between said drive shaft and said second side wall and comprising a race secured to the second side wall of the casing, a race secured to the drive shaft, interposed bearing elements constructed to operate with said races to constrain said cylinder barrel against both axial and radial movements relative to the casing, said cylinder barrel having a recess in each end, anti-friction devices disposed in said recesses mounted directly on the pintle and surrounded by and supporting the cylinder barrel on the pintle at both ends and maintaining positive clearance between the barrel and the pintle and constraining them to relative axial movement such as would be due to expansion and contraction, said anti-friction bearing devices comprising inner and outer races and interposed rolling elements, one of said races being movable axially relatively to the part other than the rolling elements with which it is in contact, said drive shaft closing one of said recesses and having a flange secured to the adjacent end of the cylinder barrel, reactance means and a surrounding stator ring insertable through the open side of the annular wall and surrounded by the latter, and anti-friction bearing assemblies disposed completely inwardly of the side walls and supported between and solely in said reactance means and stator ring.
